ATTORNEY

UNITED STATES PATENT OFFICE

OSCAR SANDERS, OF ST. JOSEPH, MISSOURI

MAIL BOX HOLDER

Application filed September 9, 1929. Serial No. 391,267.

This invention relates to a mail box holder, the general object of the invention being to provide an attractive device, with means for enabling the box to be swung to a position where mail can be placed in the same or removed therefrom without leaving a vehicle positioned on a road adjacent the box, and a person using the box can remove mail therefrom or place mail therein without stepping onto the road or crossing the gutter at the edge of the road.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawings wherein like characters denote like or corresponding parts throughout the several views, and in which:—

Figure 1 is an elevation of the device.

Figure 2 is a top plan view.

In these views, the numeral 1 indicates a post positioned adjacent one side of a road, as shown in Figure 1, and having eye bolts 2 therein and 3 indicates an angle shaped arm having the vertical portion passing through the eye bolts so that the horizontal portion can be swung to various positions. A brace 4 connects the outer end of the horizontal portion with the lower part of the vertical portion. The mail box 5 is suitably attached to the outer end of the horizontal portion. A figure 6, preferably a representation of Uncle Sam, is positioned in rear of the post 1, with one hand grasping the upper part of the post and with the feet resting upon the ground, the parts being so constructed that when the post has its lower end placed in a hole in the ground or preferably in concrete 7 placed in the hole, the feet of the figure 45 will rest on the ground, as shown in Figure 1. The horizontal part of the arm 3 should be made long enough that the box can be reached by a person in a vehicle on the road, without causing the vehicle to be run into a ditch or gutter alongside the road.

When mail has been removed from the box or placed therein, the parts can be swung to a position where there will be no danger of the parts being struck by a vehicle on the road and then when it is desired to reach the box, a person in a vehicle can simply reach over and seize a part of the device and draw the box to a position where the mail can be placed in the box or removed therefrom.

This invention also permits the user to remove mail from the box or place mail therein without crossing the gutter at the side of the road and the box can be swung out of the way when the road is being repaired by a road machine.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A mail box holder comprising a base embedded in the ground adjacent a roadway and having a socket opening outwardly through the top surface thereof, a vertical post having the lower end embedded in the base adjacent the socket, eye bolts secured to the post, a L-shaped support having the vertical portion thereof extending through the eye bolts and received in the socket and bearing against the bottom wall thereof, a brace connected to the horizontal portion of the support and to the vertical portion below the lowermost eye bolt to prevent vertical displacement of the vertical portion from the socket and from the post, and brackets attaching a mail box to the horizontal portion.

In testimony whereof I affix my signature.
OSCAR SANDERS.
